UNITED STATES PATENT OFFICE.

JOHN B. ROHRER, OF PHILADELPHIA, PENNSYLVANIA, ASSIGNOR TO
SAMUEL COOPER AND JOHN HALL, OF SAME PLACE.

DESIGN FOR A LOUNGE.

Specification forming part of Design No. 6,492, dated March 11, 1873.

To all whom it may concern:

Be it known that I, JOHN B. ROHRER, of Philadelphia, Pennsylvania, have invented a Design for a Lounge, of which the following is a specification:

The figure in the accompanying drawing fully represents my design for a lounge, the principal features of which are the moldings A and B at the back, the front molding D, and the rounded end E of the lounge.

The molding A is curved throughout, except at the point a, where it is straight, and is ornamented by elaborate carving, forming rosettes and scrolls, as shown. The shorter end molding B is of the peculiar shape represented, and terminates at the top in a scroll,

b, similar to that at the adjacent end of the molding A. The front molding D follows the curve of the arm of the lounge, and is ornamented by carving and by tablets x x directly over the feet of the lounge, as shown.

I claim—

The design for a lounge, substantially as described and represented in and by the accompanying drawing.

In testimony whereof I have signed my name to this specification in the presence of two subscribing witnesses.

JOHN B. ROHRER.
